CIRCULAR-TYPE ANTENNA WITH SYMMETRICALLY MOVABLE ARMS PROVIDING CAPACITIVE AND INDUCTIVE VARIATION FOR TUNING

John B. Caraway, Newburgh, Ind., assignor to Electronics Research, Inc., Evansville, Ind., a corporation of Indiana

Filed June 6, 1962, Ser. No. 200,580
 1 Claim. (Cl. 343—744)

This invention relates to antennae for radio apparatus and more particularly antennae for use in high frequency transmission systems. One example of the type of antenna involved is shown in Patent No. 2,467,961, issued to John B. Caraway, Jr., and H. Kees on April 19, 1949.

High frequency antenna systems are well known in the art, however, these known systems exhibit certain disadvantages. One of the disadvantages is that of frequency limitation imposed upon the antenna systems by the nature of their construction.

Accordingly, it is an object of this invention to provide an improved high frequency antenna system which obviates the above mentioned disadvantage.

It is another object of this invention to provide an improved circular type high frequency antenna which may be easily adjusted over a relatively broad range of frequencies.

It is still another object of this invention to provide an improved circular type antenna which can be tuned over a relatively wide range of frequencies by varying the inductance of the antenna.

It is still another object of this invention to provide a circular type antenna which can be tuned over a relatively wide range of frequencies by adjusting the inductance as well as the capacitance of the antenna.

It is still another object of this invention to provide an improved circular type antenna in which the inductance and input impedance can be varied.

Briefly, in accordance with aspects of one illustrative embodiment of this invention, I provide a segmented circular type high frequency antenna in which the ends of the segments of the circle are mounted on a block in such a manner that the ends of the segments may be moved relative to each other, thereby varying the diameter of the circle. This variation causes the inductance of the antenna to be varied.

In accordance with other aspects of this invention, capacitor plates are connected to the opposite ends of the segments from the mounting block and the distance between these capacitor plates will be varied in the same direction as the diameter of the circle. Thus, the capacitance of the antenna will be varied simultaneously with the inductance.

In accordance with still other aspects of this invention, I connect to the feed line with a flexible strap a feed strap clamp on the circular antenna. Advantageously, the clamp is provided with an adjustable coupling so that the clamp may be loosened and displaced relative to the segment of the circle, thereby changing the effective input impedance of the antenna.

These and various other objects and features of the invention will be more clearly understood by a reading of the detailed description in conjunction with the drawing in which:

FIG. 1 is a plan view of one illustrative embodiment of this invention;

FIG. 2 is a view in elevation of the embodiment of FIG. 1; and,

FIG. 3 is a side view of FIG. 2.

Referring now to the drawing, there is depicted a loop block 11 having a loop mounting plate 12 secured there-

2

to by any convenient means such as by welding. A pair of circular segments or semi-circular conductors 13 and 14 terminate at one end in rectangular blocks 15 which blocks are threaded to receive suitable bolts 16 which pass through the plate 12 to threadably engage the blocks 15.

The segment 13 includes a pair of spaced circular conductors while segment 14 includes a pair of spaced circular conductors with T section 17, shown in FIGS. 2 and 3, lying on its side with one end connected to block 15 and the other ends connected to the spaced circular conductors. It is understood that the spacing between the conductors of a pair is arbitrary while spacing between the pairs of conductors determines the inductance of the antenna.

Advantageously, elongated slots 18 are provided in the loop mounting plate 12, such that the bolts 16 may be loosened and the semi-circular loops or segments 13 and 14 displaced relative to each other and the bolts 16 subsequently tightened. Variation of this relative displacement varies the inductance of the antenna. On the opposite ends of the antenna segments 13 and 14 from the mounting block 11, a pair of capacitor plates 19 are mounted in substantially parallel relationship. The capacitance of this capacitor will be varied as the plates are displaced relative to each other. Thus, the capacitance of the antenna will be varied at the same time that the inductance is varied. The means used to adjust the antenna to change the diameter of the pairs of semi-circular segments can be any number of structures such as lead screws, spacers, cams, slots in a backup plate as shown in the drawing or any means that would change the diameter and thereby increase or decrease the inductance of the loop antenna.

35 A feed-through insulator or bushing 21 is secured to the loop block by suitable means such as by bolt 22 and nuts 24, 26 and 28. An O ring 29 is mounted between bushing 21 and block 11 to provide a moisture seal. Bolt 22 is connected to a suitable conductor 30 which passes through the insulating bushing 32 in a direction substantially perpendicular to bolt 22.

40 A clamping member 34 is clamped to circular segments 14 by suitable means such as a pair of nut and bolt assemblies 37. Advantageously, a flexible conducting strap 38 is connected to the bolt 22 between nuts 24 and 26 and is connected to clamp 34 to supply high frequency energy to the segment 14. Since these bolt assemblies 37 may be loosened and the clamp 34 moved relative to the segment 14, the point at which energy is supplied to the antenna and thus the input impedance is varied. It is understood, of course, that the loop mounting plate is grounded or connected to the other side of the feed line to which conductor 30 is connected to provide the necessary return path for the electrical energy.

55 When it is desired to vary the frequency at which the antenna is adjusted, bolts 16 are loosened and the segments 13 and 14 are moved relative to each other to change the distance between the segments which distance is indicated by the double-headed arrow 20. When the segments have been moved relative to each other, the bolts 16 are again tightened. This adjustment of the antenna varies the inductance by changing the distance indicated by the double arrow 20 and also changes the capacitance because it changes the distance between the capacitor plates 19 indicated by the double-headed arrow 42. After the antenna segments 13 and 14 are adjusted and tightened, the bolt assemblies 37 are loosened and the feed strap clamp 34 is moved along the segment 14 to thus modify the input impedance of the antenna to compensate for changes in input impedance caused by the relative movement of the semi-circular conductors.

This may be accomplished by well known techniques of trial and error to determine the point of maximum power transfer. After this point is located, the bolt assemblies 37 are tightened and the antenna is ready for operation.

It is understood, of course, that the antenna is preferably mounted in a horizontal plane as viewed in FIGS. 2 and 3 of the drawing. It is also understood that the segments 13 and 14, while shown to contain two substantially parallel conductors connected together at the ends, this antenna may include a greater number of circular segments such as for example 6 or 8 substantially parallel semi-circular tubes connected at their ends.

It is further understood that this antenna is suitable for both transmitting and receiving high frequency waves and that various physical sizes may be employed to determine the overall band of frequency to which the antenna may be tuned.

While I have shown and described one illustrative embodiment of this invention, it is understood that the concepts thereof may be applied to other embodiments without departing from the spirit and scope of this invention.

What is claimed is:

A circular-type antenna comprising a pair of identical semi-circular conductors, a capacitor plate permanently mounted in a fixed position on one end of each conductor, a mounting bracket affixed near the other end of each conductor, a mounting plate for supporting each of said brackets with said conductors held symmetrically in

5 conductive contact to constitute a circular conductor opened at a gap between said capacitor plates, cooperative adjustable means in said brackets and said mounting plate for moving both said conductors apart the same amount to vary the distance between said capacitor plates while maintaining the inductive component of the antenna identical in both conductors, and a feed line constituting the sole conductive connection to said semi-circular conductors coupled at a position of predetermined feed line impedance established on said conductors.
